Attorney.

UNITED STATES PATENT OFFICE.

WILLIAM H. BANDS, OF SOUTHMONT BOROUGH, PENNSYLVANIA.

FENDER.

Application filed September 20, 1922. Serial No. 589,310.

To all whom it may concern:

Be it known that I, WILLIAM H. BANDS, a citizen of the United States, and a resident of the borough of Southmont, in the 5 county of Cambria and State of Pennsylvania, have invented certain new and useful Improvements in Fenders; and I do hereby declare the following to be a full, clear, and exact description of the invention, such 10 as will enable others skilled in the art to which it appertains to make and use the same.

My invention relates generally to a fender which is particularly adapted for use 15 in connection with electric traveling cranes for the purpose of pushing men and materials from the tracks as the crane is being traversed thereon so that the wheels or other portions of the apparatus will not 20 contact with them.

This fender is particularly adapted to prevent accidents to workmen who may be on or about the crane runway and if one should be in the way of the moving apparatus, my fender will push him away without damage. Ordinarily it is only the 25 hands or the feet of the men that are likely to be run over while the rest of their persons is otherwise supported, so that the pushing action of my fender will merely 30 displace the foot, hand or leg of the workman without causing him to fall and without hurting him. My fender is also equally applicable to any kind of moving vehicle, 35 such as, street cars, railway cars of various types, etc.

One of the particular features of my invention resides in its application to an electric traveling crane provided with tracks 40 having wheel stops, which stops are ordinarily formed from plates of steel or a casting firmly secured to the ends of the track rails and extending upwardly therefrom to contact with the wheels. An ordinary fender if applied to the carriage of a 45 crane would be bent and damaged by contacting with the stop. By means of my invention I obviate this difficulty and provide a stop which while operative under all 50 usual conditions is moved away from the wheel stop automatically as it approaches it, in such a manner as to prevent its contact there-with.

My fender is preferably hinged to the 55 crane carriage and is provided with guides adapted to contact with inclined slides ad-

jacent to the track so that as the fender approaches the stop the two portions thereof open and permit the wheel to contact with the stop without touching the fender. The 60 fender is also provided with springs or other means for closing together the parts of the fender into operative position as it moves away from the stop.

Where there is only one crane on a runway this should be fitted with fenders on both sides, but where there are two cranes, the fenders need only be on one side of each.

Having thus given a general description of my invention, I will now, in order to 70 make the matter more clear, refer to the annexed sheet of drawings which form part of this specification and in which like characters of reference refer to like parts.

Figure 1 is a top plan view of a crane 75 with my fender attached thereto; Figure 2 is a side elevation of Figure 1; Figure 3 is a detail side elevation of the fender and enough of the crane to show how it is attached, and Figure 4 is a perspective view 80 of one half of one of the guard members of the fender.

Referring now to the characters of reference on the drawings. 1—indicates the crane in general; 2—are the tracks on 85 which it is adapted to operate; 3—are the crane runway girders which support the crane; 4—are the bumpers or stops secured at and to the ends of the crane rails 2; 5—are the inclined slides adapted to open 90 and close the two portions of the fender; 6—are the wheels of the crane carriage adapted to contact with the stops 4 to limit the crane movement; 7—are stationary U-shaped members secured to the crane carriage 95 to which the movable portions 8 of my fender are pivotally attached. The hinge members 9 are provided on the U-shaped portion 7 and other movable hinge members 10 are secured to the moving parts 100 8 and co-operate there-with. These members have hinge pin portions 11, as illustrated, which fit in corresponding sockets in the other hinge members. Springs 12 are provided, secured to the U-members 7 and 105 8 adapted to contact with the moving portions 8 to keep them in their normally closed positions as illustrated. 13—is a pin adapted to limit the movement of the springs 12.

Outwardly projecting flanges 14 are provided at the lower edges of the movable members 8 and roller guides 15 are rota- 110

tively mounted near the outer edge thereof to contact with the slides 5 to open the fender and prevent its contact with the stop 4.

- 5 My fenders are each thus seen to be made of two similar parts pivotally mounted on a stationary portion and are adapted to be opened as the crane nears the stops in such a manner that the fender does not contact 10 with the stop; and as the crane moves away from the stop the fender automatically closes by the action of the springs, so as to immediately come into operative position again.
- 15 Although I have shown and described my invention in considerable detail, I do not wish to be limited to the exact and specific details thereof, as shown and described, but may use such modifications in, substitutions 20 for, or equivalents thereof, as are embraced within the scope of my invention or as pointed out in the claims.

I claim:

1. A fender comprised of two portions, 25 each of which is pivotally mounted at one end, a guide on each portion and inclined slide-ways secured to the track structure

adapted to co-operate there-with, for the purpose of separating said portions, whereby contact with the track stop is prevented. 30

2. A fender comprised of a pair of portions with inclined surfaces, each of which is pivotally mounted, guides on each portion, slides secured to the track structure adapted to co-operate with said guides, and 35 springs adapted to normally hold the two portions together.

3. A crane fender comprising a fixed portion secured to the carriage thereof, hinges mounted thereon, a fender of tapering form 40 composed of two similar portions separated in the plane of the crane stop; said portions being provided with hinges adapted to co-operate with the hinges aforesaid, springs 45 for normally holding the two portions together; guides on each portion, and inclined slides adapted to co-operate there-with, to open and close the movable portions of the fender to prevent contact thereof with the stop. 50

In witness whereof I hereunto affix my signature.

WILLIAM H. BANDS.
